UNITED STATES PATENT OFFICE

ROLAND RUSSELL ROBERTS AND WORTHY J. F. FORWARD, OF ROCHESTER, NEW YORK, ASSIGNORS TO CONSOLIDATED MACHINE TOOL CORPORATION OF AMERICA, OF ROCHESTER, NEW YORK, A CORPORATION OF DELAWARE

HYDRAULIC FEED MECHANISM FOR RADIAL DRILL SPINDLES

Application filed July 26, 1928. Serial No. 295,601.

This invention relates to improvements in machine tools, and more particularly to the class of machines employing a rotating tool spindle, and has for an object to afford a simplified, practicable, and efficient mechanism for feeding such a tool spindle by fluid pressure means.

In a more particular aspect, the invention has for its object to afford a construction and arrangement requiring a minimum number of parts and located within a small compass, for controlling the feed of a rotary tool spindle by fluid pressure.

A further purpose of the invention is to provide a construction that permits applying fluid pressure to a tool spindle at some point between the ends of the spindle, as for instance by surrounding the latter with a fluid pressure operated piston and cylinder, so as to impart the necessary feeding movements to the tool spindle in an efficient manner and with a structure of simple and convenient design that gives proper support to the tool spindle.

To these and other ends the invention comprehends the structure and arrangement of parts that will appear clearly from the following description when read in conjunction with the accompanying drawings, the novel features being pointed out in the claims following the description.

In the drawings:

Figure 1 is a side elevation of a radial drill incorporating a preferred embodiment of the invention;

Figure 2 is a plan view, with parts removed and partially in section, the rail and tool head being swung around with relation to the support;

Figure 3 is an enlarged side elevation with parts broken away, showing the fluid pressure cylinder and carrier sleeve partially in section;

Figure 4 is an enlarged end elevation, partially in section on line 4—4 of Figure 3,

showing the tool spindle in lowered position, the pressure cylinder, and controlling parts;

Figure 5 is a similar view with the tool spindle elevated to its uppermost position 50 in the carrier sleeve;

Figure 6 is a horizontal sectional view on line 6—6 of Figure 5;

Figure 7 is a plan view of the tool spindle carrier and associated parts:

Figure 8 is a sectional view taken approximately on line 8—8 of Figure 2;

Figure 9 is a sectional view taken approximately on line 9—9 of Figure 8, and

Figure 10 is a sectional view taken approximately on line 10—10 of Figure 8.

The invention is susceptible of application in a variety of ways and to machine tools of different general types, and for convenience of illustration it is disclosed in this application as adapted to a radial drill that includes a column or supporting standard 1, upon which is vertically adjustable a bracket 2, while 3 is a horizontal rail or arm pivotally mounted within the bracket 2.

The bracket 2 includes overhanging flanges or plates 4 cooperating with vertical guides 5, see Figures 1 and 2, and is adjustable vertically with reference to the supporting column 1 by means of a motor 6 through a screw and nut or other suitable gearing which forms no essential part of the invention herein and is therefore unnecessary to disclose in detail. The rail 3 is held in its adjusted radial position on bracket 2 by a suitable lock controlled by a bell crank 7 and operating rod 8, the latter being governed by fluid pressure through a cylinder 9 and pipes 10, such fluid pressure operation being regulated by a valve, operated from a rod 11 which carries a controlling handle 12. Mounted for horizontal adjustment on the rail 3 is a tool head, the construction and operation of which will now be described.

21 designates tracks, while 22 is a main 90

supporting plate forming part of the tool head and adjustable on said tracks. Referring to Figures 3 to 5 inclusive, 23 designates a fluid pressure cylinder clamped to the plate 22 by means of bolts 24 or other suitable attaching means, while 25 and 26 designate stuffing boxes at the bottom and top of said cylinder for a purpose now to be made clear.

Extending through said cylinder and movable endwise thereof is a carrier, preferably in the form of a sleeve and including a lower piston portion 27 provided with a piston 28 movable in said cylinder, and an upper portion 29 extending above the cylinder and 10 rigidly connected to the lower portion 27 by threading or otherwise. The sleeve or carrier just described is movable endwise of the cylinder through the stuffing boxes 25 and 26 from the position shown in Figure 4 15 to that shown in Figure 5 in order to feed the tool spindle, which latter extends through the cylinder and sleeve already described and is surrounded thereby, in order to afford a simplified and economical structure as well as 20 one that is sufficiently rigid to give proper support and bearing to the tool spindle, and to house the parts within a minimum space.

31 designates the tool spindle that is journalled as shown within the sleeve-like carrier and movable endwise therewith when the latter is operated in one direction or the other, by the introduction of fluid pressure into one end of the cylinder 23. The tool spindle 31 is rotatable within its carrier, and 30 to this end carries at its upper end a spur gear 32 engaged and driven by a spur gear 33 that is slidably keyed to the driven shaft 34. The gears 32 and 33 are enclosed within a suitable housing 35 at the top of the spindle 35 carrier and said gear assembly is movable vertically with the tool spindle endwise of the driven shaft 34, the slidable connection between the gear 33 and shaft 34 permitting such movement of the gearing while maintaining a constant driving connection to the 40 tool spindle.

The driven shaft 34 carries at its lower end a bevel gear 36 that is operated by a bevel pinion 37 slidably keyed on driving shaft 38, 50 see Figure 2, whereby the entire tool head assembly is movable endwise of the driving shaft 38 to permit adjustment along the rail 3. The driving shaft 38 carries a pulley 39 that is operated through suitable belts from 55 a pulley 40 on the armature shaft of an electric driving motor 41, which furnishes the necessary power to the parts on the tool head just described. The driven shaft 34 is arranged within a suitable vertically disposed 60 housing that is provided with vertical tracks 42, see Figure 7, engaged by overhanging flanges or plates 43 secured to the tool spindle carrier, thereby insuring a smooth balanced control of the tool spindle as it is fed 65 vertically.

In order to effect the necessary movement of piston 28 within the cylinder 23, the stuffing boxes or cylinder heads 25 and 26 are provided with openings 51 and 52 respectively, see Figure 3, to which fluid or hydraulic pressure is conducted from a pump indicated generally at 53, and mounted on plate 22, power to the pump being furnished from the aforementioned driving shaft 38 through pulleys 54 and 55 and the interconnecting belts. The operation of the pump 53 and control of fluid pressure to the cylinder 23 is effected by the hand lever 56, such controlling mechanism as well as the construction of the fluid pressure pump being of conventional form known in the art of fluid pressure controlling mechanisms, and further disclosure of such parts is considered unnecessary for an understanding of the present invention, which has to do with the structure by which fluid pressure control is operatively associated with a rotating tool spindle of a machine tool.

70 In order to effect the necessary lateral adjustment of the tool head along the tracks 21, a rack 61 is provided at the underside of the upper track 21, see Figures 1, 4 and 8, and 62 is a spur gear engaging said rack and formed on an arbor 62 that is provided at its opposite end with a worm gear 63 driven by a worm 64 on shaft 65. The latter carries a clutch designated generally at 66 which is shiftable so as to operate the shaft 65 from either one of the bevel gears 67 which are moved in opposite directions from a bevel gear 68 on shaft 69. The shaft 69 is operated constantly from the driving shaft 38 through bevel gears 70 and 71, see Figure 2, gear 70 being slidably keyed on the shaft 38.

75 The clutch 66 is controlled by a clutch shifter 72 that is fixed on a rocker arm 73, see Figures 8 and 9, the latter being shiftable upon operation of the hand lever 74. It will be understood that normally the clutch 66 is disengaged from gears 67, and is brought into engagement with one or the other of said gears by operating hand lever 74 when it is desired to shift the tool head horizontally along the rail 3 to change the position of the tool with reference to the work.

80 While the invention has been described in its application to a particular machine tool, it is not confined to the structure shown, and this application is intended to cover any other arrangements, modifications or adaptations 100 coming within the intent of the invention or the scope of the following claim.

85 We claim:

90 In a machine tool, the combination with a tool carrier, a sleeve movably mounted in said carrier, a tool spindle journalled in said sleeve, a piston mounted on the sleeve exteriorly thereof, a cylinder in which the piston is movable by fluid pressure to move the sleeve and the spindle, a driven shaft 95

tively to which the spindle moves, a gear rotated by the driven shaft and fixed to the spindle for driving the same, an arm, guideways on said arm arranged transversely to the feed movement of the spindle, a drive shaft arranged parallel with said guideways, guides on the carrier slidably engaging said guideways, and gearing supported by the carrier and movable longitudinally of said drive shaft for establishing operative connection 10 between the drive shaft and the driven shaft.

In witness whereof, we have hereunto signed our names.

ROLAND RUSSELL ROBERTS.
